TAG DISPLAY UNIT

Harold I. Sides, 9% Tote-Cart Company, 226 W. Superior St., Chicago, Ill., assignor, by mesne assignments, to Harold I. Sides and Kitty Bell Sides, both of Chicago, Ill.

Filed Oct. 1, 1959, Ser. No. 843,700
11 Claims. (Cl. 46—308)

This invention relates to price tag displays, more particularly to a price tag display unit for use on grocery bins and the like, and to a display bin having a price tag unit attached thereto.

Modern day supermarkets which include in their inventory literally thousands of different types of items, quite often use display bins such as those shown in my patent Serial No. 407,688 issued January 13, 1959, which by this reference is made a part hereof. It is, of course, necessary to indicate in some way the price of goods contained in such display bins. Such price indicators should, of course, be readily changeable and should be easily attachable to the display bins. Further, it is desirable that they be attachable to the display bins in such a manner that youngsters will be unable to remove or displace them.

It is, therefore, an object of this invention to provide a tag display unit which answers the above requirements.

It is a further object of this invention to provide a tag display unit for use on such grocery bins which includes a backing member for attaching the unit to the grocery bin, a tag holder supporting portion on the backing member and a transparent tag holder positioned on the supporting member and adapted to carry price tags, and the like, which are maintained in a substantially vertical position so as to be easily read by customers.

It is yet another object of this invention to provide a display bin for small packaged articles such as groceries, and the like, which includes an upwardly extending front portion and a tag display unit attached thereto such as that described in the preceding paragraph.

Other objects and advantages of this invention will become apparent from the following description of several embodiments taken together with the accompanying drawings.

Of the drawings:

FIGURE 1 is a partial perspective view of a display bin having the tag display unit of this invention attached thereto;

FIGURE 2 is an exploded perspective view of one embodiment of the tag display unit of this invention;

FIGURE 3 is a partial rear elevational view of the tag display unit in place on the display bin;

FIGURE 4 is a view in section taken along the line 4—4 of FIGURE 3;

FIGURE 5 is a side view similar to FIGURE 4 of another embodiment of the tag display unit of this invention;

FIGURE 6 is a partial front elevational view of the embodiment of the tag display unit shown in FIGURE 5 in place on a display bin;

FIGURE 7 is a partial sectional view taken along the line 7—7 of FIGURE 5;

FIGURE 8 is a side elevational view of a tag display unit resting on a substantially plane surface.

FIGURE 9 is a partial perspective view of a display bin having another embodiment of the tag display unit of this invention attached thereto;

FIGURE 10 is a partial rear elevational view of the tag display unit shown in FIGURE 9 in place on the display bin; and

2

FIGURE 11 is a sectional view taken along the line 11—11 of FIGURE 10.

Referring now to FIGURE 1, a display bin 10 similar to that shown in my patent referred to above is partially shown therein. This display bin is constructed of a wire material and has an upwardly extending front wall 11, an upwardly extending rear wall 12 and a divider 13. The front wall 11 is shorter than the rear wall 12 and the divider 13, and is constructed so as to angularly extend upwardly and outwardly from the display bin. A tag display unit 14 is shown in place on the angularly extending front wall 11.

Referring now to FIGURE 2, there is seen therein an exploded view of the tag holder 14. This structure is also constructed for the most part of wire material or the like, and includes an elongated backing member 15 which has a hooked upper portion 15a and a protruding lower portion 15b.

Attached to the backing member 15 is an L-shaped tag holder supporting member 16. The attachment between the supporting member 16 and the backing member 15 is by means of welds at points 17 and 18 at the rear portion of the shorter leg 16a of the tag holder 16. The upper portion 16b is not necessarily connected to the backing member 15 but may rest against it as shown in FIGURE 4 or may be spaced from it as shown in the embodiment of FIGURE 8 which will be described later.

The tag holder supporting member 16 has defined on its front face an angularly disposed tag holder supporting portion 19. Attached thereto by means of welds 20 and 21 is a tag retainer bar 22. The extreme ends of the tag retainer bar 22 are curved forwardly to provide hooks 22a which are adapted to grip the tag holder.

The tag holder shown in this embodiment comprises a thin substantially flat sheet 23 which as shown is made of a transparent plastic material but which could be constructed of other materials with equal facility. The upper and lower edges 23a of the sheet 23 are turned inwardly to form channels 24. These channels 24 are adapted to receive a price tag or the like 25 and to hold it in place. A pair of sockets 26 are provided on the back edges of the sheet 23. These sockets 26 are adapted to receive the hooks 22a on the tag retainer bar 22 to thus position the tag holder properly in place. A cover 27 which is made of a transparent plastic material also has its edges 27a turned back to create the channels 28. This cover member 27 is adapted to enclose the sheet 23 with the price tag 25 in place to protect the latter.

Referring now to FIGURE 5, another embodiment of the tag display unit 14 of this invention is shown therein. As can be seen, this embodiment of the unit includes an L-shaped tag holder supporting member 29 which has an upper hooked portion 30 and a downwardly extending portion 31 at the end of the shorter leg 29a of the tag holder supporting member. The downwardly extending portion 31 and the hooked portion 30 combine to provide substantially the function of the backing member 15 already discussed. The tag holder supporting member 29 has an angularly disposed tag holder supporting portion 32 very similar to the tag holder supporting portion 19 already discussed. A tag bar 22 is also attached to this portion 32 and also has hooked ends 22a. A short bar 33 is welded across the tag holder supporting member near the downwardly extending portion 31. This bar 33 is designed to abut the display bin as will be described later.

Referring now to FIGURE 8, a second embodiment of a tag holder 34 is shown as part of a tag display unit similar to that shown in FIGURE 2. The tag holder 34 is a flat piece of transparent plastic material which has an open tubular center 35. This tubular center 35 is designed to receive the hooks 22a of the tag retainer

bar 22. The ends 34a of the tag holder are turned over to provide the channels 36. A second pair of channels 37 are defined in the center of the tag holder by the strips 38. Each channel 36 and its opposed channel 37 cooperate to provide a slot for receiving a tag similar to, but smaller than tag 25 shown in FIGURE 2.

Referring now to FIGURE 9, another embodiment of a tag display unit 114 is shown in place on a display bin 10. This unit is designed for use on bins located on or near the bottom of a display rack (not shown) and thus near the floor of a store. In such a location it is desirable to have the tag holder tilted to a greater degree thus allowing the customer an easy view of the same.

The unit 114 is also constructed for the most part of wire material or the like, and includes an elongated backing member 115 which has a hooked upper portion 115a. The lower portion of the member 115 has an S-shaped bend at 115b which provides an outwardly displaced parallel portion 115c.

Attached to the backing member 115 is a V-shaped tag holder supporting member 116. The attachment between the supporting member 116 and the backing member 115 is by means of welds at points 117 at the top of the member 115 and 118 near the lower portion of the member 115.

The tag holder supporting member 116 has defined on its front face an angularly disposed tag holder supporting portion 119. Attached thereto by means of welds 120 and 121 is a tag retainer bar 122. The extreme ends of the tag retainer bar 122 are curved forwardly to provide hooks 122a which are adapted to grip the tag holder. The tag holder shown on this embodiment is the same as the tag holder shown in and described in FIGURE 2.

In use, the tag display units 14 and 114 of this invention are attached to the display bin 10 by hooking the hook portions 15a, 30 and 115a over the bar 39 which is part of the front wall 11. The lower portions 15b, 31 and 115c are dipped behind the wire 40 which is also part of the front wall 11 at the same time the hooks are put in place over the bar 39. This provides for substantially rigid but removable attachment of the tag holder display unit to the display bin 10. In such a position, the rear portions 16a, 116a and 16b of the tag holder supporting members 16 and 116 of the embodiments shown in FIGURES 2 and 9 will abut the vertical wires 41 of the front wall 11 to provide a stop and thus giving the rigid attachment discussed above. The same function is performed by the bar 33 in the embodiment shown in FIGURES 5 and 6. Of course, it should also be noted that it is not necessary to dip the lower portion 15b, the downwardly extending portion 31, or the portion 115c behind the wire 40 if rigid attachment is not needed. This is so because the tag display unit will hang neatly in place with the rear portions 16a, 116a and 16b of the tag holder supporting member 16 and the bar 33 abutting the vertical wires 41. In such a condition, the tag display unit may be moved easily from display bin to display bin.

Referring once again to FIGURE 8 it can be seen therein that the unit 14 may be deposited on a horizontal planar surface 42 supported by the lower portion of the backing member 15a and the lower part of the tag holder 34a. In such a condition, the information displayed on price tags or the like in channels 36 and 37 would be immediately visible to the purchasing public.

Having thus described my invention as related to the embodiments shown in the accompanying drawings, it is my invention that the invention be not limited by any of the details of description unless otherwise specified, but rather be construed broadly within its spirit and scope as set out in the accompanying claims.

I claim:

1. A tag display unit for use on wire grocery bins and the like, comprising: an elongated backing member including a hook-shaped upper portion for attaching said

unit to said grocery bin, the lower portion of said backing member adapted to be dipped behind a portion of said grocery bin to effect a substantially rigid connection; a tag holder supporting portion on said backing member having an angularly disposed first portion adapted to support said tag holder and a second portion adapted to abut said grocery bin when said unit is attached thereto; a substantially thin and flat tag holder positioned on said supporting portion having a plurality of channels adapted to carry price tags and the like; and a removable transparent cover having a pair of channels adapted to receive said holder to protect said tags, the lower portion of said backing member and the lower portion of said tag holder being adapted to support said unit on a substantially horizontal surface in a displaying position.

2. A tag display unit for use on wire grocery bins and the like, comprising: an elongated backing member including a hook-shaped upper portion for attaching said unit to said grocery bin, the lower portion of said backing member adapted to be dipped behind a portion of said grocery bin to effect a substantially rigid connection; a tag retainer supporting portion on said backing member having an angularly disposed first portion adapted to support said tag retainer and a second portion adapted to abut said grocery bin when said unit is attached thereto; a horizontally disposed tag retainer on said first portion having hook-shaped ends; and a substantially thin and flat transparent tag holder positioned on said tag retainer and having end sockets adapted to receive the hook-shaped end portions thereof, said tag holder also having a plurality of channels adapted to carry price tags and the like, the lower portion of said backing member and the lower portion of said tag holder being adapted to support said unit on a substantially horizontal surface in a displaying position.

3. A tag display unit for use on wire grocery bins and the like, comprising: an elongated backing member including a hook-shaped upper portion for attaching said unit to said grocery bin, the lower portion of said backing member adapted to be dipped behind a portion of said grocery bin to effect a substantially rigid connection; a tag retainer supporting portion on said backing member having an angularly disposed first portion adapted to support said tag retainer and a second portion adapted to abut said grocery bin when said unit is attached thereto; a horizontally disposed tag retainer bar on said first portion having hook-shaped ends; a substantially thin and flat tag holder positioned on said tag retainer and having end sockets adapted to receive the hook-shaped end portions thereof, said tag holder also having a plurality of channels adapted to carry price tags and the like; and a removable transparent cover having a pair of channels adapted to receive said holder to protect said tags, the lower portion of said backing member and the lower portion of said tag holder being adapted to support said unit on a substantially horizontal surface in a displaying position.

4. A tag display unit for use on wire grocery bins and the like, comprising: an elongated backing member including a hook-shaped upper portion for attaching said unit to said grocery bin, the lower portion of said backing member adapted to be dipped behind a portion of said grocery bin to effect a substantially rigid connection; a tag holder supporting portion on said backing member having an angularly disposed first portion adapted to support said tag holder and a second portion adapted to abut said grocery bin when said unit is attached thereto; a substantially thin and flat tag holder positioned on said supporting portion having a plurality of channels adapted to carry price tags and the like; and a removable transparent cover having a pair of channels adapted to receive said holder to protect said tags.

5. A tag display unit for use on wire grocery bins and the like, comprising: an elongated backing member in-

cluding a hook-shaped upper portion for attaching said unit to said grocery bin, the lower portion of said backing member adapted to be dipped behind a portion of said grocery bin to effect a substantially rigid connection; a tag retainer supporting portion on said backing member having an angularly disposed first portion adapted to support said tag retainer and a second portion adapted to abut said grocery bin when said unit is attached thereto; a horizontally disposed tag retainer on said first portion having hook-shaped ends; and a substantially thin and flat transparent tag holder positioned on said tag retainer and having end sockets adapted to receive the hook-shaped end portions thereof, said tag holder also having a plurality of channels adapted to carry price tags and the like.

6. A tag display unit for use on wire grocery bins and the like, comprising: an elongated backing member including a hook-shaped upper portion for attaching said unit to said grocery bin, the lower portion of said backing member adapted to be dipped behind a portion of said grocery bin to effect a substantially rigid connection; a tag retainer supporting portion on said backing member having an angularly disposed first portion adapted to support said tag retainer and a second portion adapted to abut said grocery bin when said unit is attached thereto; a horizontally disposed tag retainer bar on said first portion having hook-shaped ends; a substantially thin and flat tag holder positioned on said tag retainer and having end sockets adapted to receive the hook-shaped end portions thereof, said tag holder also having a plurality of channels adapted to carry price tags and the like; and a removable transparent cover having a pair of channels adapted to receive said holder to protect said tags.

7. A tag display unit for use on wire grocery bins and the like, comprising: a tag supporting frame having a hook-shaped member adjacent one end thereof; means adjacent the other end of said frame, shaped to extend behind a supporting surface on said bin; and a member located adjacent the end of said means and positioned to engage a front area of said supporting surface whereby a portion of the supporting surface is gripped between said means and said member to provide substantially tight connection thereto.

8. A tag display unit for use on wire grocery bins and the like, comprising: a frame having a hook-shaped mem-

ber adjacent one end thereof; means adjacent the other end of said frame shaped to extend behind a supporting surface on said bin; a tag holder supporting portion on said frame; and a member located adjacent the end of said means and positioned to engage a front area of said supporting surface whereby a portion of the supporting surface is gripped between said means and said member to provide substantially tight connection thereto.

9. A tag display unit for use on wire grocery bins and the like, comprising: a frame having a hook-shaped member adjacent one end thereof; means adjacent the other end of said frame, shaped to extend behind a supporting surface on said bin; and a tag holder supporting portion on said frame having a first portion adapted to support a tag and a second portion positioned adjacent the end of said means to engage a front area of said supporting surface whereby a portion of the supporting surface is gripped between said means and said supporting portion to provide a substantially tight connection thereto.

10. A tag display unit for use on wire grocery bins and the like, comprising: a frame having a hook-shaped member adjacent one end thereof; means adjacent the other end of said frame, shaped to extend behind a supporting surface on said bin; a tag holder supporting portion on said frame having a first portion adapted to support a tag and a second portion positioned adjacent the end of said means to engage a front area of said supporting surface whereby a portion of the supporting surface is gripped between said means and said supporting portion to provide a substantially tight connection thereto; and a tag holder positioned on said supporting portion.

11. The device of claim 10 wherein said tag holder supporting portion has a plurality of channels adapted to carry price tags and the like.
